UNITED STATES PATENT OFFICE

DAMIEN MEREDIEU, OF ANGOULEME, FRANCE

UNIVERSAL PRESS

Application filed August 24, 1925, Serial No. 52,249, and in France September 1, 1924.

This invention relates to presses and has for its object the provision of a universal press the relation of whose parts may be so interchanged and reorganized that while at 5 one time it may function as an ordinary flat press, it may also act selectively as a printing press of the direct roller-inked type; as a press for printing matter through an inked ribbon in simulation of typewriting or in another reorganization of its parts as a book 10 binding press.

Other objects of the invention will appear as the following description of a preferred embodiment thereof proceeds.

15 In the drawings in which the same characters of reference are used to denote similar parts in the several views,

Fig. 1 is a perspective view of the press assembled so as to print simulated typewritten 20 text.

Fig. 2 is a perspective view in detail showing the paper holding and relief mechanism.

Fig. 3 is a perspective view showing the ribbon feeding mechanism which is brought 25 into requisition when the press is assembled to print typewritten matter.

Fig. 4 is a perspective view of the type bed and paper holding mechanism.

Fig. 5 is a perspective view of the ink plate 30 used in connection with the type bed shown in Fig. 4.

Fig. 6 is a perspective view of the sub-frame upon which the type bed travels.

Figs. 7 and 8 show in perspective modified 35 forms of an auxiliary frame used in connection with the upper press plate to form a sewing press.

Fig. 9 is an arrangement of certain of the 40 press parts, shown in perspective, arranged to constitute a book binding press.

Referring now in detail to the several figures, and first advertiring to the assemblage shown in Fig. 1 the line xx represents the division between two distinct parts of the press 45 of which that shown to the right of said line will first be described. It consists of a platen p resting at the front and back upon cleats q and being hingedly secured to a base or table A at its forward side by means of hinges 50 x'' . Thus in certain adaptations of the press

the platen together with the cleats q may be swung axially of its hinges to a position perpendicular to that shown in Fig. 1 which perpendicular position is shown in Fig. 9 and the use of which will be described in due 55 course.

At the sides of the platen and resting freely upon the table A are standards h . These form guides for the movable part of the press and also supports for the beam a of the press 60 which extends transversely between said standards adjacent the top and is securely fixed thereto in any suitable manner. A screw c extends through a threaded socket b at the middle of the press beam and enters a socket 65 in the movable transverse member h to which the upper press plate o is secured. The screw is retained in the socket of the movable member h by means of a retaining collar e .

The upper press plate o is suitably and 70 detachably secured to the member h by means of a flat bar r extending transversely of the upper press plate on its top side and having bolts projecting through apertures in the movable member h and fixed by nuts x . The 75 movable member h is formed with hollow cylindrical extremities which cooperate slidably with the standards h . The screw is operated by a handle d . Since in certain adaptations of the press the upper press plate o 80 will be inverted, it is provided on its upper surface with feet t arranged so as to afford a three point base of support when the upper press plate is inverted.

Beneath the platen p the standards h are 85 connected by a fixed transverse member a^2 to which the platen is detachably secured by means of a flat bar r^2 secured to the underside of said platen in the middle and from which bolts project downwardly through registering apertures in the member a^2 . The underside of the platen is provided near its rearward end with a similar bar r^3 from which similar bolts extend so that in certain relative positions of the parts the standards together with the member a^2 may be disconnected from the central bar r^2 and connected to the end bar r^3 .

A pair of auxiliary legs y is pivotally attached to the standards h adjacent their 100

upper ends which may support said standards and their appurtenant parts in those arrangements of the press in which the lower ends of the standards do not rest upon the table A.

5 In the ordinary operation of the press in so far as it has been described and as it is shown in Fig. 1 it is similar to an ordinary letter press the upper press plate being arranged to come down compressively upon any 10 object placed upon the platen p .

When it is desired to use the flat press as a book binding press as shown in Fig. 9, the platen p is swung axially of its hinges through an angle of 90° carrying with it the standards 15 and their associated parts which then extend horizontally. The standards and the lower transverse member a^2 are then disconnected from the central bar r^2 of the platen, and connected to the similar bar r^1 adjacent the rearward end of the platen which end is now at the top. The auxiliary legs are swung at an angle of 90° so as to extend perpendicularly downward and to rest upon a suitable support which is here represented as an extension B 20 of the table A. The legs are held rigidly in this position by tightening the nuts z . Preferably the upper press plate is also removed leaving only the bar r between which and the platen the leaves of the books to be bound 25 may be compressed by extending vertically. This arrangement of the press is shown in Fig. 9.

When it is desired to use the press as a printing press of the roller-inked type the 30 flat press is used in the position shown in Fig. 1, the unit shown to the left of the line xx being brought up against it and secured thereto by means of bolts b^2 extending from one 35 unit through suitable apertures in the other unit and removably affixed thereto by means of wing nuts b^1 . The second unit comprises a frame a^1 of suitable construction which in itself is not material to the invention upon which parallel guides c^1 are arranged leading 40 toward the platen p . In these guides, which 45 may be of any suitable construction is placed the subframe y^2 carrying anti-friction bearings u^2 adapted to run along the guides. The type bed c^1 is placed upon the subframe y^2 50 and rendered movable therewith in a longitudinal direction by means of studs v^2 formed on opposite sides of the subframe which project into apertures v'' formed in the side 55 member b^3 of the type bed. These side members extend over the longitudinal members of the subframe and beyond the sides of the type bed, the latter fitting down within the space 60 between the sides of the subframe. The under sides of the side members b^3 are formed 65 with apertures c^3 into which extend pins w^2 arising from the subframe, said pins being 70 surrounded by springs x^2 which afford a cushion support for the type bed. In the embodiment of the invention shown in the drawings the upper ends of the apertures c''' are

closed by plates c^3 set into the side members b^3 . It is obvious that these plates are not an essential feature of the invention. The type bed is adapted to carry a chase z^2 allocated by suitable clips a^3 and suitable quoins a''' , the means for supporting and allocating the chase being, of course, immaterial and optional with the user of the press. The composition f' is set in the chase by means of the usual furniture.

At the forward end of the type bed is the paper handling mechanism, shown in detail in Fig. 2 comprising a bar h'' secured to said type bed and supporting a rod a'' on which are mounted two wire frames t' and y' . Across the frame t' is stretched a fabric sheet u' upon which is suitably mounted a card v' having the usual locating pins s^2 for holding the card or paper on which the proof is printed. The frame t' is provided with handles w' and x' by which it may be manually raised or lowered upon the type. The frame y' is the relieving frame. It has cross wires y''' against which the sheets of paper to be printed rest and it is provided with springs z' for automatically raising it to an upright position when the frame t' is raised, thus lifting the printed sheets from the type and holding them in a substantially vertical position permitting their easy removal from the press. It may be sometimes desired to hold the frames t' and y' down to the type in the preliminary making ready of the press, for which purpose a pivot pin d^3 is affixed to one of the side members b^3 of the type bed and adapted to project over said frames when they are in horizontal position.

A plate e'' is provided having an ink spreading surface f'' . This plate has end tenons o'' adapted to fit in slots e^3 opening on the inner sides of the side members b^3 at the rear of the type bed, the plate e'' snugly fitting between said side members. The plate e'' is provided with an operating handle g'' by means of which the entire type bed together with a subframe y'' may be reciprocated back and forth on the guides d' being alternately moved between the platen and upper press plate of the flat press and beneath the inking rollers the arrangement of which will now be described.

The support for the inking rollers as shown comprises a third unit C of the press which is brought up against the second unit and it may be secured thereto if desired. The roller support comprises end pieces c'' having pairs of shallow slots alternating with pairs of deeper slots. The end pieces c'' and the depth of the slots are so ordered that when the rollers t'' are in the deeper slots they make contact with the inking surface f'' in a forward position of the type bed and make contact with the printing surface of the type in a backward position of the type bed. Thus by pushing the type bed rearward and then for-

wardly through its full range of movement the rollers t'' first pick up ink from the inking surface f'' , then spread it upon the type after which the type is moved forwardly beneath the flat press, the paper holding mechanism being meanwhile turned down upon the type by contact of said mechanism with the rearward edge of the upper plate of the flat press. By a slight turn of the screw c the paper is printed after which the screw is slightly backed off and the type bed pulled back. Upon emergence of the paper holding mechanism from beneath the upper press plate o , the frames t' and y' are thrown to the position shown in Fig. 4 through the action of the springs z' . The printed sheet is then removed. The position of the type bed when beneath the flat press is definitely determined by means of lugs s^1 extending from the sides of the side members b^3 and making contact with the standards h in the full forward position of the type bed. Since in distributing the ink it is generally desirable to draw the type bed backwardly to a point beyond the roller t'' , extension guides d'' provided at the rearward side of the press.

When it is desired to print through a ribbon, for the purpose of simulating typewritten matter the printing rollers are rendered inoperative by placing them in the shallow slots. This raises them above the level both of the inking surface f'' and the surface of the types so that they no longer function. An auxiliary ribbon holding and feeding device is now brought into play which is shown in detail in Fig. 3. It consists of a frame i having side members k'' the ends of which project as shown at f^2 . This frame is set down over the type, the projecting ends f^3 being received by retaining loops f''' fixed to the type bed. Between the side members k'' of the ribbon holding frame are rollers i' upon which the ribbon j' is alternately wound and unwound. Between the rollers, the ribbon j' stretches above the type. It is normally kept from touching the type by means of a rectangular wire support k' maintained by springs t' in an upward position higher than the plane of the printing surface of the type. When the pressure of the printing plate o comes upon the ribbon the support k' is depressed against the pressure of said springs bringing the ribbon into contact with the type.

The ribbon is automatically wound upon one or the other of the rollers by the following instrumentalities:—A rod n' is provided which normally lies horizontally and parallel with one of the side members k'' of the ribbon holding frame. This rod has hinged ends only one of which is left extended at a time the other one being manually up-folded as shown in q' of Fig. 3 to render the said end inoperative. The other hinged end acts as a pawl. The rollers are provided with ratchet

wheels m' in the path of whichever of the ends of the rods n' may be extended. The said rod is mounted for vertical reciprocation upon studs o' and it is normally held in an upper position by means of a spring p''' . The up-turned end of the rod m' is above the plane of the type surface so that when the press plate o comes down toward the type it first contacts with the up-folded end q' depressing the rod m' . This causes the pawl formed by the extended hinged end of the rod n' to ride over one or more of the teeth of the ratchet wheel which it engages. When the printing of a sheet has been completed and the upper press plate is withdrawn the rod n' rises under the expansion of the spring p''' and the extended end being rigid in this direction acts as an advancing pawl to rotate its associated ratchet wheel m' thus winding the ribbon upon the associated roller. When all of the ribbon has been wound upon this roller the operator of the press extends the previously folded end q' and folds the end that previously has been extended thus reversing the direction of the winding operation.

Printing in this instance is carried on as before, the type bed with a ribbon holding frame being advanced beneath the flat press as far as lugs s' will permit and printing pressure then being applied by means of the screw d . It will be noted that the handle g'' is bent so as to return upon itself forming a loop which extends over the rollers, bringing the end of the handle into such proximity to the handle d that both handles can be conveniently handled by a person standing at the side of the press. A paper holder t^2 is shown, the supplying of this feature being a matter of convenience but not materially affecting the invention.

It is frequently found convenient to use the upper press plate as the base of a sewing press. For this purpose, it is dismantled from the press structure and inverted, resting upon the sheet t , shown in Fig. 8. Auxiliary standards p'' are then provided connected at their top being transverse bar r'' above the slots s in said press plate. A further modification of this construction is shown in Fig. 7 in which the transverse cross piece r'' is adjustable for height along screw threaded portions of the standards, the height of said cross member being determined by the position of the nuts a' .

While I have in the above description disclosed what I believe to be a preferred and practical embodiment of my invention it is obvious that numerous departures from the specific details as shown may be made without departing from the spirit of the invention as defined in the appended claims.

Having thus described my invention, what I claim as new and desire to secure by Letters Patent is:—

1. A combined binding and printing press including in combination, a support, printing mechanism, a platen, the latter being hingedly carried by said support and having its free end normally adjacent to, and detachably secured to said printing mechanism, a press frame operatively associated with said platen, including standards and a transverse member slidable thereupon, a screw operated press plate detachably secured to said transverse member and cooperating therewith, said platen being swingable to a position at an angular distance of 90° to its normal printing position, said press frame being likewise swingable, means for detachably securing said press frame to the free edge of said platen when the latter is disengaged from said printing mechanism to permit said platen and press frame to be swung to their relative right-angular position with respect to their normal positions, said platen then serving as a support for said press frame in its new position, and auxiliary standards carried by said press frame for assisting in supporting the latter.

2. A combined binding and printing press including in combination, a support, printing mechanism, a platen, the latter being hingedly carried by said support and having its free end normally adjacent to, and detachably secured to said printing mechanism, a press frame operatively associated with said platen, including standards and a transverse member slidable thereupon, a screw operated press plate detachably secured to said transverse member and cooperating therewith, said platen being swingable to a position at an angular distance of 90° to its normal printing position, said press frame being likewise swingable, means for detachably securing said press frame to the free edge of said platen when the latter is disengaged from said printing mechanism to permit said platen and press frame to be swung to their relative right-angular position with respect to their normal positions, said platen then serving as a support for said press frame in its new position, and auxiliary standards carried by said press frame for assisting in supporting the latter, said auxiliary supporting means being swingably mounted on said standards.

3. A combined binding and printing press including in combination, a support, printing mechanism, a platen, the latter being hingedly carried by said support and having its free end normally adjacent to, and detachably secured to said printing mechanism, a press frame operatively associated with said platen, including standards and a transverse member slidable thereupon, a screw operated press plate detachably secured to said transverse member and cooperating therewith, said platen being swingable to a position at an angular distance of 90° to its normal print-

ing position, said press frame being likewise swingable, means for detachably securing said press frame to the free edge of said platen when the latter is disengaged from said printing mechanism to permit said platen and press frame to be swung to their relative right-angular position with respect to their normal positions, said platen then serving as a support for said press frame in its new position, and auxiliary standards carried by said press frame for assisting in supporting the latter, said transverse member being adapted to operate directly with said platen, in pressing relation thereto, upon removal of said press plate.

In testimony whereof I have signed my name to this specification.

DAMIEN MEREDIEU.
